MARKING MACHINE

John B. Hadaway, Swampscott, and Robert N. Sandberg, Beverly, Mass., assignors to United Shee Machinery Corporation, Paterson, N. J., a corporation of New Jersey

Application January 22, 1937, Serial No. 121,861

22 Claims.

(Cl. 33—4)

This invention relates to marking machines and is herein illustrated as embodied in a machine adapted for indicating the contour to which the sole edge of a shoe is to be trimmed.

5 As pointed out in copending application Serial No. 119,555, filed on January 8, 1937, in the name of C. G. Brostrom, the sole edge trimming operation can be facilitated by making a series of guide marks indicating the desired extension of the sole 10 edge from the upper at various points about the forepart.

A general object of this invention is to increase the accuracy and speed of a marking operation of this type, and to relieve the operator of the 15 care and judgment which the operation requires to a greater extent than has been possible heretofore.

In accordance with this object, the present invention contemplates the automatic control of the 20 spaced relation between a marking tool and a shoe positioning guide, in accordance with the different sole extensions it is desired to indicate. To this end, one feature of the invention consists of means for limiting the approach of the tool 25 and the guide before the tool is moved into engagement with the shoe, this means comprising a member adapted to be moved into a different position for each sole extension and which is thus moved from one position to another each time the tool is operated to mark the shoe.

30 As herein illustrated, this means comprises a stop having lobes of different size on its periphery and adapted to be moved as the tool approaches the guide to present a different portion of its periphery to a part of the tool operating mechanism each time the tool is operated. Thus, any sequence of different sole extensions may be 35 indicated on a shoe by successive marking movements of the tool in the use of the illustrated machine, it being necessary merely to provide a stop the periphery of which is shaped with reference to the desired sole extensions.

Further to facilitate the marking operation as 40 carried out by the illustrated machine, it is constructed and arranged to carry the marking tool through a complete cycle of its movement with great speed and a minimum of effort on the part of the operator. To this end, the marking tool is moved against the light resistance of a yielding member into its marking position by a short 45 movement in one direction of means actuated by the operator, which means is released after the tool has engaged the shoe to permit the tool to be automatically returned to its starting position under the influence of the above-mentioned yielding member.

Invention is also to be recognized in the provision of a carrier for the marking tool having means cooperating with a guide to move the marking tool into engagement with an inking

member before the tool engages the shoe so that a fresh application of ink or other suitable marking medium is imparted to the tool prior to each marking operation.

These and other features of the invention will 5 appear more fully from the following detailed description when read in connection with the accompanying drawings and will be pointed out in the claims.

In the drawings,

Fig. 1 is a view in perspective illustrating a machine in which the invention is embodied;

Fig. 2 is a plan view illustrating the forepart of a shoe before its sole edge is trimmed and marks made by the illustrated machine indicating the 15 desired sole edge extension at various points about the forepart;

Fig. 3 is an elevation of the machine viewed 20 from the side opposite to that seen in Fig. 1; and

Fig. 4 is a side elevation similar to Fig. 3 but illustrating the relation of the parts of the machine and a shoe when the latter is marked.

The illustrated machine, as mentioned above, is 25 adapted to impart a series of marks A, B, C, D and E (Fig. 2) to the upper surface of the sole edge extension of a shoe S as guides for the edge trimming operator who is to trim the sole edge to a contour indicated by these marks. In carrying out this marking operation, the operator presents the shoe S to the illustrated machine so that a 30 guide 10 abuts the side of the upper (Fig. 4) 35 adjacent to the locality of the sole edge extension it is desired to mark and then, by depressing a treadle (not shown), a work support 12 is moved upwardly against the bottom of the sole of the shoe, thereby to hold the shoe against the guide 10, and later a marking tool 14 is moved into engagement with the sole edge extension at a predetermined distance from the adjacent portion of the upper. This operation may be repeated at as 40 many places as is necessary clearly to indicate the desired contour to which the sole edge is to be trimmed; but the illustrated machine, as will 45 more fully appear below, is arranged to make a mark at five different points about the forepart, each mark being at a predetermined distance from the upper.

The guide 10 is fixed at all times during the 50 operation of the machine, being clamped to the upper part of the machine frame 16 by a screw 18 threaded into the guide 10 and passing through a slot 20 in the frame 16 to permit adjustment of the guide 10 toward and away from the tool 14. The support 12 is rotatably mounted on a screw 22 threaded in a hinged member 24 at such 55 an angle that the conical surface of the support 12, when it is moved upwardly, as will be described later, holds the sole edge extension directly against the lower end of the guide 10. For the purpose of adjusting the angular relation 60

between the support 12 and the guide 10, the block 24 is hinged to the head of a stem 26, on a pin 28 carried by the stem 26 and passing through the upper portions of flanges integral with the block 24 and arranged closely to embrace opposite sides of the head of the stem 26. The support 12 is held in any desired position of adjustment by a bolt 30 which passes through an elongated slot in the stem 26 and is arranged to clamp the flanges of the block 24 firmly against the stem. Vertical movement of the work support 12 is permitted by a sliding connection between the stem 26 and a bearing 32 extending from the frame 16, rotation of the stem 26 being prevented by abutting vertical surfaces 34, 34 on the head of the stem 26 and frame 16. The work support 12 is thus operated to hold a work-piece against the guide 10 by a lever 36 pivoted at 38 to the frame 16. In order to provide for vertical adjustment of the support 12 the lower portion of the stem 26 has threaded thereon a flanged nut 40 between the sides of which is received the forward end of the lever 36. A lock nut 42 is arranged to hold the nut 40 in any desired position of adjustment on the stem 26. The lever 36 is swung in a clockwise direction (Figs. 3 and 4), to elevate the work support 12 and to cause the shoe S to be held against the guide 10, by a spring 44 which connects the lever 36 with the bottom of the frame 16. This action of the work support 12 occurs whenever the machine is treadled, as a result of which a rod 46, passing through a bifurcation at the right-hand end of the lever 36 and carrying a collar 48 arranged normally to support the arm 36 against the tension of the spring 44, is lowered. The rod 46 is connected at its upper end to a lever 50 pivoted to the frame 16 on a stud 52, the lever 50 normally being urged in a clockwise direction by a spring 54 which is considerably stronger than the spring 44 and extends between the lever and the frame 16. Movement of the lever 50 in this direction is adjustably limited by a set screw 56 threaded in the lever and adapted to bear against a boss 58 formed on the frame 16. The lower end of the rod 46 is arranged to slide in a hole 60 formed in the base of the frame 16 directly beneath the point of connection of the rod 46 to the lever 50.

When the machine is treadled the rod 46 is first lowered and then quickly returned to its normal inoperative position, illustrated in Fig. 3, under the influence of the spring 54, by the mechanism now to be described. A treadle rod 62 connected to a lever 64 pivoted at 66 to the frame 16, when lowered as by treading the machine, moves downwardly a latch 68 pivoted on the forward end of the lever 64 and arranged to engage a collar 70 fixed to the rod 46. A spring 72 connecting the latch 68 and the lever 64 normally holds the latch hooked over the collar 70, but near the bottom of the stroke of the rod 46 a projection 74 on the base of the frame 16 engages a tail 76 of the latch 68, causing the latter to be swung out of engagement with the collar 70 and thereby permitting the spring 54 quickly to return the rod 46 and other machine parts associated therewith to their inoperative position in which they are illustrated in Fig. 3.

While the work support 12 is being moved upwardly to hold the shoe against the guide 10 in the manner above described, the tool 14 is moved toward the guide 10, receives an application of marking medium such as ink for example, and

then, the shoe being held in the desired position between the guide 10 and the work support 12, the tool 14 is moved into engagement with the shoe at a predetermined distance from the upper without the use of any care on the part of the operator other than that required to insure that the shoe is positioned properly with respect to the guide 10 as described above.

Each actuation of the tool causes it to pass through a sequence of events comprising its approach to the guide 10, during a short interval of which the tool is suddenly moved into engagement with the inking roll 104, the engagement of the work by the tool, and finally the retraction of the tool to its starting position without engaging the inking roll. This operation of the tool is accomplished by the following mechanism. The tool 14 is held by a bolt 78 in a carrier 80 which is pivoted at 82 to a lever 84 mounted to rock about the stud 52. The lever 84 has formed integrally therewith an arm 86 adapted to be engaged by a screw 88 threaded in the lever 50. The arm 86 and the screw 88 are normally held in engagement by a coiled spring 90 one end of which is looped about a part of the lever 84 and the other end of which is bent about another lever 92 also arranged to rock about the stud 52. A rod 94 fixed at the bifurcated lower end of the lever 92 is bored to receive the reduced lower end of a link 96 which is pivoted at 98 to the central portion of the carrier 80. Thus the spring 90, acting through the lever 92 and the link 96, yieldingly holds the carrier 80 against a guide roll 100 rotatably mounted in the upper part of the frame 16. As the carrier 80 and tool 14 are moved toward the guide 10, a pawl 102 mounted on the carrier 80 engages the roll 100 and causes the carrier 80 to swing down about the pivot 82 until the tool is moved into engagement with an ink roll 104 from which the tool receives an application of ink or other marking medium. The roll 104 is rotatably mounted in a reservoir 106 holding ink or other suitable marking medium into which the roll 104 dips as it rotates, as indicated in Fig. 4. The roll 104 is thus rotated by the tool 14 to present a fresh portion of its surface to the tool each time it is moved into engagement with the work. The reservoir 106 is closed at its upper side by a cover 108 through which the roll 104 extends and is supported on the frame 16 by a spring clip 110. Shortly after the tool 14 engages the roll 104 the upper end of the pawl 102, the tail of which is normally held by a spring 112 at the bottom of a recess 114 in the carrier 80, is swung by contact with the roll 100 in a counterclockwise direction into the recess as the direction of the pressure between the roll 100 and the pawl 102 moves across the pivotal axis of the pawl from right to left (Fig. 4), permitting the carrier 80 to re-engage the roll 100 and causing the tool 14 to jump away from the inking roll 104, as indicated by the path of the tool illustrated in Fig. 3. As the tool 14 approaches the guide 10, a roll 116 mounted on the lever 84 at 118 engages a stop 120 detachably fixed to a shaft 122 rotatably mounted in the frame 16.

The stop 120 is provided with a plurality of lobes having different radii determined with reference to the different distances between the marks A, B, C, D and E and the respective portions of the upper adjacent thereto. The stop 120 is rotated each time the marking tool 14 is actuated by connections comprising a link 124 pivoted at one end to the lever 50 and at its other

end to a lever 126 pivotally mounted on the frame 16 by means of a screw 128. The rear end of the lever 126 is slotted to receive a stud 130 carried by a swivel member 132 arranged to swing about the shaft 122. The swivel member 132 carries a pawl 134 adapted to engage a ratchet wheel 136 having one tooth for each desired position of the stop 120. Retrograde movement of the stop 120 is prevented by a pawl 138 pivoted at 140 on the frame 16, the pawl normally being held in engagement with the ratchet wheel 136 by a spring 142. It will now be apparent that before the tool 14 has reached the end of its movement toward the guide 10 the stop 120 will have been rotated to bring a different portion of its periphery into position to be engaged by the roll 116 whereby the required spacing of the mark with respect to the upper is predetermined and automatically changed as different parts of the forepart of the shoe are presented in succession to the marking tool. The stop 120, as herein illustrated, has only three lobes because the marks B, C and D on the illustrated shoe are required to be uniformly spaced from the upper, the marks A and E each being differently spaced from the upper. It is to be understood, however, that the stop 120 is to be shaped with reference to the required position of the marks and that it might have five lobes having different radii.

After the tool 14 has been positioned with respect to the guide 10 by engagement of the roll 116 with the stop 120, further counterclockwise rotation of the lever 84 is prevented and the lever 50 is then swung away from the arm 86 and into engagement with a screw 144 threaded in the lever 92 which, acting through a spring 146 interposed between the shaft 94 and a washer 148 locked on the end of the link 96, yieldingly moves the tool 14 downwardly into engagement with the shoe to mark it. Toward the latter part of the downward stroke of the rod 46 and after the tool 14 has been moved into engagement with the shoe to mark it, the pawl 68 strikes the projection 74 and is moved out of engagement with the collar 70, thereby permitting the rod 46 to rise suddenly under the influence of the spring 54. The first effect of the rise of the rod 46 and lever 50 is the raising of the tool 14 from the work, this movement being followed as the screw 88 strikes the arm 86 by movement of the carrier 80 to its rearmost position, determined by the engagement of the screw 56 with the boss 58. While the carrier 80 is thus being retracted, the collar 48 engages the rearmost end of the lever 36 which is then swung in a counterclockwise direction to lower the work support 12. Thus, practically instantly after the making of one mark on the shoe the machine is ready to be retreaded to make a succeeding mark the position of which with respect to the upper will be automatically determined by the stop 120 which, as described above, is rotated each time the tool is caused to mark the work.

Having thus described our invention, what we claim as new and desire to secure by Letters Patent of the United States is:

1. In a marking machine, a guide shaped and arranged to engage the upper of a shoe adjacent to its welt crease, a marking tool, means for moving said tool successively toward said guide and then into engagement with the shoe to mark it, a member for controlling the relative position of the guide and tool as the tool is moved into engagement with the shoe, said member being movable into a plurality of different positions in

accordance with the desired sole extension, and mechanism operated by said means for positioning said member each time the tool is moved into engagement with the shoe.

2. In a marking machine, a guide shaped and arranged to engage the upper of a shoe adjacent to its welt crease, a marking tool mounted for movement toward said guide and into engagement with the shoe to mark it, said guide and tool being movable relatively to each other whereby the position of the mark on the shoe may be varied, means for positioning said tool and guide relatively to each other comprising a member adapted to be moved into a different position for each desired spaced relation of said guide and tool, means for operating said tool, and connections between said operating means and said member for causing said member to be moved from one position to another before said tool engages the shoe.

3. In a marking machine, a guide shaped and arranged to engage the upper of a shoe adjacent to its welt crease, a marking tool mounted for movement toward said guide and into engagement with the shoe to mark it, said guide and tool being movable relatively to each other to determine the position of the mark on the shoe, marking tool operating means, means for controlling the relative position of the tool and guide when the tool engages the shoe, and connections arranged to cause the last-mentioned means to be actuated by said operating means.

4. In a marking machine, a guide shaped and arranged to engage the upper of a shoe adjacent to its welt crease, a marking tool, means for operating said tool constructed and arranged successively to move said tool toward said guide and into engagement with the shoe, means for adjustably limiting the movement of said tool toward said guide, and connections actuated by said tool operating means for positioning the last-mentioned means.

5. In a marking machine, a guide shaped and arranged to engage the upper of a shoe adjacent to its welt crease, a marking tool mounted for movement successively toward said guide and into engagement with the shoe, means for limiting the movement of said tool toward said guide, said means being adapted to be moved into a plurality of positions, and mechanism for moving said means between successive positions each time said tool is operated to mark the shoe.

6. In a marking machine, a guide shaped and arranged to engage the upper of a shoe adjacent to its welt crease, a support movable toward said guide to hold a shoe thereagainst, a marking tool, means for moving said tool successively toward said guide and then into engagement with the shoe, a stop cooperating with said means to limit the movement of said tool toward said guide, said stop being movable into any one of a plurality of positions, and means for setting said stop as said tool is moved toward said guide.

7. In a marking machine, a guide shaped and arranged to engage the upper of a shoe adjacent to its welt crease, a marking tool, means for moving said tool toward said guide and into engagement with the shoe, a stop adapted to be set in a number of positions thereby adjustably to limit the movement of said tool toward said guide, and connections actuated by said means for setting said stop.

8. In a marking machine, a guide shaped and arranged to engage the upper of a shoe adjacent to its welt crease, a marking tool, means comprising

ing members arranged to yield relatively to each other for moving said tool toward said guide, a stop cooperating with one of said members to limit the movement of said tool toward said guide, and means cooperating with the other of said members for moving said tool into engagement with the shoe.

9. In a marking machine, a guide shaped and arranged to engage the upper of a shoe adjacent to its welt crease, an arm having a marking tool thereon, a lever pivoted to said arm and mounted for movement so as to cause said tool to approach said guide, links connected to said arm for moving said tool into engagement with the shoe, an operator-controlled member for actuating said lever and links, and yielding means arranged normally to hold said lever and member in engagement with each other.

10. In a marking machine, a guide shaped and arranged to engage the upper of a shoe adjacent to its welt crease, an arm carrying a marking tool, a member connected to said arm mounted and arranged to move said tool laterally of said guide, means cooperating with said member for adjustably limiting its above-mentioned movement, links for moving said arm to cause said tool to engage the shoe, and operator-controlled means cooperating successively with said member and one of said links to move said tool laterally of said guide and then into engagement with the shoe.

11. In a marking machine, a guide shaped and arranged to engage the upper of a shoe adjacent to its welt crease, a marking tool, an arm carrying said tool and mounted to swing so as to move said tool toward said guide and into engagement with the shoe, a stop for limiting the movement of said tool toward said guide, an operator-controlled member, and connections between said arm and member actuated by said member to move said tool into engagement with said shoe.

12. In a marking machine, a marking tool, an arm carrying said tool and mounted for movement between an inoperative and a marking position, an inking member, a guide arranged to control the movement of said arm, and a pawl carried by said arm and adapted to cooperate with said guide to move said tool into engagement with said inking member as said arm approaches its marking position.

13. In a marking machine, a marking tool, a carrier for said tool mounted for movement between an inoperative and a marking position, a guide for said carrier, and an inking member, said carrier having a projection adapted to engage said guide as said carrier moves toward its marking position thereby to cause said tool to engage said inking member.

14. In a marking machine, a marking tool mounted for movement between an inoperative and a marking position, an inking member, a carrier for said tool, means for guiding said carrier, and means on said carrier arranged to engage said guiding means during the movement of said tool toward its marking position thereby to move the tool into engagement with said inking member.

15. In a marking machine, a marking tool, a carrier for said tool mounted for movement between an inoperative and a marking position, an inking member, and means actuated by movement of said carrier toward its marking position for moving said tool into engagement with said inking member.

16. In a marking machine, a work support, a

marking tool mounted for movement from an inoperative position into engagement with a shoe on said support, operating means for said tool comprising a yielding member mounted and arranged to urge said tool toward its inoperative position, means for actuating said operating means thereby to mark the shoe, and means for releasing said operating means after the shoe is marked whereby said yielding member is permitted to return said tool to its inoperative position.

17. In a marking machine, a guide shaped and arranged to engage the upper of a shoe adjacent to its welt crease, a shoe support movable toward said guide to hold a shoe thereagainst, a marking tool mounted for movement from an inoperative position into engagement with said shoe, operating means arranged yieldingly to hold said shoe support and tool away from said guide, means for actuating said operating means thereby to mark the shoe, and means for disconnecting said operating means and last-mentioned means after the shoe is marked thereby to permit said operating means to return said support and tool to their inoperative positions.

18. In a marking machine, a shoe support, a marking tool mounted for movement from an inoperative position into engagement with a shoe on said support, operating means for said tool constructed and arranged normally to hold said tool yieldingly in its inoperative position, an operator controlled member, and a latch normally connecting said member and operating means, said latch being mounted and arranged to release said operating means after the shoe has been marked.

19. In a marking machine, a marking tool, an inking member, a carrier for said tool mounted for movement between an inoperative and a marking position, a guide for said carrier adapted to engage said guide for causing said tool to be moved into engagement with said inking member, said means being mounted and arranged to yield in passing said guide whereby the contact of said tool and inking member is momentary.

20. In a marking machine, a marking tool, a shoe guide, a carrier for said tool, means for operating said carrier to cause the tool to be moved toward said guide and then into engagement with a shoe held against said guide, an inking member, and means mounted and arranged to utilize the movement of the carrier toward said guide to move said tool into engagement with said inking member.

21. In a marking machine, a marking tool, an arm carrying said tool and mounted for movement toward and away from a marking position, an inking member, a roll arranged to guide said arm, a pawl mounted on said arm to yield in passing said roll in one direction but to cause said tool to engage said inking member when moved in the opposite direction into engagement with said roll.

22. In a marking machine, a marking tool, a carrier for said tool mounted to move the latter toward and away from a marking position, a guide roll adapted to engage said carrier thereby to guide said tool, an inking member, and a pawl on said carrier mounted and arranged momentarily to move said carrier away from said roll thereby to cause said tool to engage said inking member.

JOHN B. HADAWAY.

ROBERT N. SANDBERG. 75
